UNITED STATES PATENT OFFICE

RUDOLF P. JUGEL, OF DENVER, COLORADO, ASSIGNOR TO AMERICAN BALL MILL COMPANY

GRINDING MILL

Application filed March 31, 1930. Serial No. 440,403.

My invention relates to grinding mills, and particularly to sectional linings for mill heads. A principal object of the invention is to provide such a lining, the sections of which are held in place without the use of bolts and nuts.

Another important object of the invention is to provide a sectional grate adjacent the discharge end to prevent the escape of material not sufficiently pulverized, but permit the discharge of material that has been reduced to the desired size.

Other objects reside in the provision of simple means for holding the sections in position, which may be quickly released for the removal and replacement of the sections.

A further object of the invention is to provide linings for the trunnions of the mill, which are disposed to assist in holding the head sections in position.

Novel combinations and arrangements of parts, and novel details of construction will appear in the course of the following description. In the drawings like reference characters designate similar parts in the several views.

Figure 1 is a vertical section of a grinding mill embodying the foregoing objects.

Figures 2 and 3 are semi-sections looking in the directions of the arrows 2-2 and 3-3 respectively in Figure 1.

Figures 4 and 5 are sections taken on the lines 4-4 and 5-5 respectively in Figure 1.

Figure 6 is a face view of a grate section comprised in the invention.

Figure 7 is a face view of an imperforate head section.

Figure 8 is a broken elevation, partly in section, looking in the direction of the arrow 40 "A" in Figure 1.

Referring more in detail to the drawings, standards 9 are shown for the support of bearings 10 for the mill. The mill has a shell 12 provided with channels 13 and flanges 14. Heads 15 and 16 for the mill are provided with flanges 17 and 18 respectively, which are bolted to the flanges 14 of the shell. A ring gear 19 for driving the mill is bolted to the flange 18.

The heads 15 and 16 have integral trun-

nions 20 and 22 mounted for rotation in the bearings 10. A feed inlet pipe 21 is bolted to the trunnion 20, and a bell flange 23 for the discharge of material is bolted to trunnion 22. Supported in the trunnion 20 is a liner 24 containing an internal helical groove 25. The trunnion 22 contains a liner 26 having transverse bores 27. The interior of the liner 25 tapers outwardly toward the bell flange 23. A cone 28, disposed opposite the bores 27, projects into the liner 26 for guiding material toward the bell flange 23.

The shell has a sectional lining, the sections of which are indicated at 29. Wood blocks 30 in the channels 13 and wood blocks 31 between the sections, together hold the shell lining sections 29 in position. These and other features are shown and described more in detail, and are claimed, in my pending application Serial No. 440,404, filed March 31, 1930.

The heads 15 and 16 have radial channels 48, and have circumferential flanges or rims 39 and 46 respectively. These flanges are respectively provided with channels 40 and 47 preferably aligned with the channels 13 of the shell and continuous with the radial channels 48. The head 15 and the lining therefor are provided with an opening 32 for a manhole. The hole is closed by a plug 35 to make the lining continuous. The plug has a groove 37 lined with wood, or other compressible and/or expandable strips 54.

A cover 33 for the manhole has a tongue 36 having a driving fit with the lined groove 37 of the plug. The cover thereby holds the plug in position. The cover is held in place by bolts 34 and has handles 38.

The head 15 has a lining composed of sectors, each of which has a tapering body portion 42 and flanges 43, extending along the longitudinal edges, arranged to fit in the radial channels 48. The flanges 43 have end portions 44 extending beyond the end of the body member.

As illustrated in Figure 5, the flanges 43 of the sections project into the radially arranged channels 48, and as shown in Figure 3, the end portions 44 also project into the channels 40 of the flange 39. Blocks 45 of

compressible, expandible material, such as wood, are driven into the channels 48 between the flanges 43 to hold the sections in position. The sections extend from the flange 39 to the trunnion liner 24.

Sections 49 for the head 16 have slots or other apertures 50 to provide grates for the passage therethrough of material that has been sufficiently pulverized. The sections 10 have flanges 51 to be inserted in the channels to assist in holding the sections in place, similar to those shown at 43 on the sections 42, with the exception that the flanges 51 are wider to provide passages 52 between the sections 49 and the head 16. The blocks 45 are also employed to hold the sections 49 in place. The passages 52 formed by the grate sections connect with the transverse bores 27.

It is to be understood that in the rotation 20 of the drum, the flanges 51 on the grate sections lift the material so that it will flow out of the passages 52 and into the outlet trunnion 26 for its discharge through the bell flange 23.

It will be noted that the heads 15 and 16 are hollow and the body portions are disposed at angles to the vertical and that the sections of the liners therefor are disposed at the same angles and have their end faces 30 at obtuse angles to their axes. Moreover, the trunnion liners 24 and 26 project into the mill at least enough to provide a support or rest for the sections. Even though the blocks 45 between the sections become dislodged or 35 broken, the sections will be wedged or lodged in place between the flanges 39 and 46 and the shell lining sections on the one hand and the trunnion liners on the other hand. When in such positions, the sections cannot become 40 dislodge except by shearing off some of the metal of the sections or liners.

In the operation of the mill, material is fed into the shell by the helical groove in the inlet trunnion liner 24. The grinding 45 medium in the shell, whether balls, rods or pebbles, pulverizes the material by rotation of the mill. The rotation is effected by driving means engaging the ring gear 19.

As the material is reduced to a sufficient 50 fineness, it passes through the slots 50 in the grate sections and into the passages 52. Rotation of the mill lifts the material and allows it to run out of the passage 52, through the transverse bores 27 and into the outlet 55 conduit 26, from which the material is discharged through the bell flange 23.

It will be apparent that the sections of the head liners are held in place without the use of bolts or nuts, and, in fact, will be held in 60 place even though the blocks therebetween are dislodged or broken.

It is to be understood that changes may be made in the details of construction and in the arrangements of parts without departing 65 from the spirit of the invention. I do not

wish to be limited to the construction and arrangement shown and described, except as specifically stated in the hereunto appended claims.

What I claim and desire to secure by Letters Patent is:

1. In a grinding mill, a shell, a channeled head closing an end of the shell, the head having a channeled flange, and lining sections for the head having flanges in the channels of the head and in the channels of the flange. 75

2. In a grinding mill, a channeled shell, a head closing an end of the shell and provided with radial channels, the head having a rim provided with channels connecting the channels of the head with those of the shell, and lining sections having flanges in the channels of the head, of the rim and of the shell. 80

3. In a trunnioned grinding mill, a head therefor, having channels radiating from the trunnion, tapering lining sections for the head having flanges in the channels, and a lining for the trunnion assisting in holding 85 the lining sections in place. 90

4. In a grinding mill, a channeled head therefor, and a sectional lining for the head, the sections having apertured body portions and flanges, the flanges being in the channels of the head and the body portions being spaced from the head of the mill to provide passages defined by the flanges, the apertures of the body portions connecting the interior of the mill with said passages, and the mill having an outlet connecting with the passages. 95 100

5. In a grinding mill, a channeled head therefor, and a sectional lining for the head, the sections having body portions spaced from the head of the mill to provide passages and having flanges in the channels of the head defining the passages, the mill having an outlet and the passages connecting the interior of the mill with the outlet. 105

In testimony whereof I hereunto affix my signature.

RUDOLF P. JUGEL.
